UNITED STATES PATENT OFFICE

MARK H. MARTIN, OF READING, PENNSYLVANIA, ASSIGNOR TO BIRDSBORO STEEL FOUNDRY AND MACHINE COMPANY, OF BIRDSBORO, PENNSYLVANIA, A CORPORATION OF PENNSYLVANIA

END SILL STRUCTURE

Application filed December 29, 1928. Serial No. 329,101.

My invention relates to end sill structure.

The principal object of my invention is to devise an end sill structure for attachment to railway cars which shall materially strengthen this portion of the car construction, provide an effective and rigid tie for the ends of the under framing, and simplify the work of assembling through a reduction in the number of necessary, separate parts.

A further object is to devise an end sill structure of the character described in the form of a one piece casting which shall comprise integral features heretofore found as individual parts and particularly facilities for performing the usual functions of the coupler striking plate and carry iron, front draft castings, and means for direct attachment of the structure to the under framing of the car.

A further object is the incorporation in an end sill structure of features which effect a general improvement in the design of devices of this character and which is susceptible of ready adaptation for use with the types of draft gears now employed.

While cast end sills are old in the art, they are usually utilized merely as a substitution for some form of structural arrangement and do not include in integral combination therewith the several advantages offered by my improved structure. As already indicated, the latter is intended to strengthen and rigidify the car end structure, and to more effectively protect against the buffing and surging stresses encountered in train operation. Through direct attachment to the car under framing, including the draft and side sills, and the diagonal bracing therebetween, not only are these basic structural elements of the car more securely tied together, but this result is accomplished with a fewer number of parts than is now common practice. In furtherance of this improved construction, the cheek flanges which are employed to secure the sill casting to the draft sills also include the front draft stops for receiving the tension load of the draft gear and flanges are formed on the end of the casting to facilitate its attachment to the side sills.

Other features comprise a special form of

construction for supporting the car flooring and also, in the case of an end opening, for protecting the floor against damage and wear during loading and unloading. The usual push pole pockets are cast integral with the sill and provision is made for passage through the casting of the train pipe.

These and further objects of my invention will be set forth in the following specification, reference being had to the accompanying drawing, and the novel means by which said objects are effectuated will be definitely pointed out in the claims. In the drawing:

Fig. 1 is a front elevation of my improved structure showing the same in position on a railway car, but with the coupler removed.

Fig. 2 is a plan view of the end sill structure, looking in the direction of the arrow 2 in Fig. 1, and showing its mode of application to the under framing of a car.

Fig. 3 is a view of the end of the structure, looking in the direction of the arrows 3 in Fig. 1.

Figs. 4 and 5 are sections along the lines 4-4 and 5-5, respectively, in Fig. 1, looking in the direction of the arrows.

Fig. 6 is a isometric view of the end sill structure.

Fig. 7 is a section similar to that shown in Fig. 5 and showing the modified arrangement employed when the structure is used in connection with a draft gear having a horizontal yoke.

Fig. 8 is a plan view of the modification shown in Fig. 7, looking in the direction of the arrow 8 in said figure.

The numeral 10 represents my improved end sill structure generally, which in the preferred form shown is intended for use with draft gears employing vertical yokes. The structure is formed as a one piece casting having upper and lower horizontal flanges 11 and 12, respectively, which are joined by a connecting web 13. Strengthening ribs 14 may be disposed at appropriate intervals between said flanges and an extension 15 projects upward as a continuation of the web 13 to form a pocket with the flange 11 for the reception of the end plank of the flooring 16.

The depth of the web 13 is increased at the

mid-portion of the casting as at 17 and is bent forward from the vertical plane thereof to form a projection 18. A passage 19 extends through said projection for the reception of the drawbar 20 of the coupler 21. Above the opening 19, the projection 18 is generally channel-shaped in section, as shown clearly in Fig. 5 with the upper limb 22 thereof being a continuation of the upper flange 11 and the vertical web 23 being flush with the front side of said projection and serving as a striking plate for the horns of the coupler 21. Below the opening 19, the projection 18 is also generally channel-shaped in section with the front limb 24 thereof being substantially flush with the lower portion of said projection and the horizontal web 25 thereof serving as a carrier for the drawbar 20.

Extending inwardly from the web 13 on each vertical side of the passage 19 are flanges 26 and at their junction with said web, projections 27 extend toward each other along the vertical sides of said passage to limit the swinging movement of the coupler when the car is rounding curves and to strengthen this portion of the structure against the impact of the drawbar during such movement. The flanges 26 form cheek plates 28 which are secured to the draft sills 29 in any approved manner and are further flanged on the inner ends thereof, as at 30, to form the front stops for the draft gear which may be strengthened by ribs 44 extending inwardly along said plates. Accordingly, a tension pull on the coupler is transmitted directly through these stops to the draft sills without the necessity for employing other parts. A slot 31 is formed in each cheek plate 28 for the reception of the usual draft key and the depth of the upper flange 11 is increased as at 32 extending back and connecting with flanges 30 to bridge the space between said cheek flanges and to thereby further strengthen the structure in locations which receive the buffing load of the coupler. As an additional mode of strengthening this portion of the casting, ribs 33 may be appropriately disposed on the undersides of the portion 32 and limb 22 of the projection 18.

The flange 11 is further increased in depth at each end of the casting, as at 34, to facilitate attachment thereto of the diagonal braces 35 and also of the side sills 36. As a further means of securing the casting to the side sills, flanges 37 are formed at each end of the web 15 and appropriately secured to said sills. Push pole pockets 38 are cast integral with the structure at each end thereof and a passage 39 is provided in the web 15 for the train pipe.

In the modification illustrated in Figs. 7 and 8, the end sill structure, represented generally by the numeral 40, is designed for use with draft gears employing horizontal

yokes. This modified form differs from that above described only in the provision of a changed form of cheek plates 41 for attachment to the draft sills 43, an open ended slot 42 being provided in each plate to receive the front draft key.

It will be obvious from the foregoing description that my improved end sill structure combines in a single casting features which have heretofore existed as separate units with the consequent necessity for their fitting and assemblage together in the building of a railway car. According to my arrangement, the required number of separate parts is not only lessened, but the unitary construction results in a more adequate tying up of the end structure of the car and a more effective resistance to the shocks applied thereto during operation. The casting is particularly strengthened in the region which is subjected to the buffing stresses of the coupler and provision is also made through the flange 11 and extension 15 for receiving the end plank of the flooring and protecting the same against wear.

While I have shown one set of elements and combinations thereof for effectuating my improved end sill structure, it will be understood that the same are illustrated for purpose of disclosure only and in nowise to restrict the arrangement to the exact forms and shapes set forth, for it will be obvious that other variations in the latter may be adopted without departing from the spirit of my invention.

I claim:

1. An end sill structure comprising an end sill, integral end flanges for attachment to the side sills, integral cheek plates for attachment to the draft sills, and a flange on the inner end of each of said cheek plates adapted to act as front stops for the draft gear.

2. An end sill structure comprising an end sill, integral end flanges for attachment to the side sills, integral cheek plates for attachment to the draft sills, said cheek plates including slots for the reception of the draft key, and means on said cheek plates adapted to act as a front stop for the draft gear.

3. An end sill structure comprising an end sill, integral end flanges for attachment to the side sills, integral cheek plates for attachment to the draft sills, said cheek plates including slots for the reception of a draft key, and a flange formed on the inner end of each of said cheek plates adapted to act as front stops for the draft gear.

4. An end sill structure comprising a one piece casting including upper and lower horizontal flanges and a connecting web, integral cheek plates extending inwardly from said web for attachment to the draft sills, and a flange on the inner end of each of said

cheek plates adapted to act as front stops for the draft gear.

5. An end sill structure comprising a one piece casting including upper and lower horizontal flanges and a connecting web, flanges on the ends of said web for attachment to the side sills and integral cheek plates extending inwardly from said web for attachment to the draft sills, the depth of said 10 upper flange being increased over said cheek flanges and at the ends of said casting.

6. An end sill structure comprising an end sill, integral end flanges for attachment to the side sills, integral cheek plates for attachment to the draft sills, and a flange on each of said cheek plates adapted to act as front stops for the draft gear.

7. An end sill structure comprising a one piece casting including upper and lower horizontal flanges and a connecting web, integral cheek plates extending inwardly from said web for attachment to the draft sills, and a flange on each of said cheek plates adapted to act as front stops for the draft gear.

25 8. An end sill structure comprising an end sill, integral end flanges for attachment to the side sills, integral cheek plates for attachment to the draft sills, said cheek plates including slots for the reception of a draft 30 key, and a flange on each of said cheek plates adapted to act as front stops for the draft gear.

9. An end sill structure comprising a one-piece casting including upper and lower horizontal flanges and a connecting web, flanges on the ends of said web for attachment to the side sills, integral cheek plates extending inwardly from said web for attachment to the draft sills, and an extension on said 40 upper flange projecting rearwardly over said cheek flanges.

10. An end sill structure comprising a one-piece casting including upper and lower horizontal flanges and a connecting web, flanges on the ends of said web for attachment to the side sills and integral cheek plates extending inwardly from said web for attachment to the draft sills, the depth of said 45 upper flange being increased at the ends of said casting.

In testimony whereof, I affix my signature.

MARK H. MARTIN.
